UNITED STATES PATENT OFFICE.

ADA HENDERSON, OF WAMPSVILLE, NEW YORK.

RUBBER PROTECTOR FOR STOCKINGS.

Application filed July 2, 1926. Serial No. 120,168.

This invention relates to a stocking protector, the general object of the invention being to provide a legging-like article preferably formed of thin rubber and designed to 5 cover the ankles and lower portion of the leg and to fit over a rubber on the shoe so as to protect the stocking from the elements as well as to keep the leg dry.

Another object of the invention is to so 10 form the device that it can be placed on the leg and its edges fastened together by snap fasteners or the like, with a flexible band for holding the lower part of the device over the instep and with a garter-like arrangement at its upper end for holding the device 15 around the calf of the leg.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:

Figure 1 is a view showing the device in 35 use.

Figure 2 is a similar view but looking toward the opposite side of the device.

Figure 3 is a view of the device in partly 40 open position.

Figure 4 is a similar view of the opposite side of the device.

Figure 5 is a section on line 5—5 of Figure 4.

Figure 6 is a section on line 6—6 of Figure 4.

As shown in these views, the device is formed of a pair of pieces 1 and 2 of thin rubber or similar material which are sewn together at the front edges, a small strip 3 being used to cover the seam. The upper portions of the strips are made full so that they will fit around the calf portions of the leg and the lower portion of the device tapers off to a rounded point 4 which is also curved so that this part of the device will fit over the instep part of the foot.

A triangular shaped member 5, formed of three pieces 6, 7 and 8, cut on the bias and sewn together, has one of its inclined edges sewn to the outer edge of the piece 2 intermediate the ends of said piece. This member 5

is adapted to fit around the rear part of the ankle and its free edge is adapted to be detachably fastened to the edge of the piece 1 by the snap fasteners 9. The free edges of 60 the pieces 1 and 2 are also provided with snap fasteners 10 at their calf covering portions for holding the device around the calf part of the leg. A band 11 of resilient material has its ends fastened to the edges of 65 the part 4 and is adapted to extend under the instep portion of the foot to hold this part 4 in place. A strip 12 of resilient material is fastened to the upper end of the device and a strip 13 of the same material 70 from which the major portion of the device is formed, is sewn to the upper edge of the device and covers the strip 12 and is gathered or pleated so as to give a garter-like effect.

The protector is placed on the leg after a rubber has been placed on the shoe. The toe is placed through the opening formed by the part 4 and the strip 11 which will hold the part 4 in a position covering the instep 80 portion of the foot. The free edge of the member 5 is then placed around the ankle and fastened to the piece 1 and then the pieces 1 and 2 are fastened together. The strips 12 and 13 will act to hold the device 85 against slipping down over the calf and as the lower portion of the device overlaps the rubber, any water running down the device will pass over the rubber. Thus the device will keep the stocking clean and dry and 90 will also keep the leg warm and dry.

It is thought from the foregoing description that the advantages and novel features of my invention will be readily apparent.

I desire it to be understood that I may 95 make changes in the construction and in the combination and arrangement of the several parts, provided that such changes fall within the scope of the appended claims.

What I claim is:—

1. A stocking protector comprising a member having its upper part shaped to fit around the calf portions of the leg of a wearer and its lower portion tapering off to a rounded point, the lower portion also being curved to fit over the instep part of the foot of the wearer, a member connected with one edge of the tapered part, fastening means for connecting the other edge of the said second member with the opposite tapered edge of the main member so that the second member will cover the rear part of

the ankle and a strap connected with the lower edges of the device and adapted to pass under the instep portion of the foot.

2. A stocking protector comprising a member for covering the leg and ankle of the wearer, said member being open, fasteners for connecting the edges together, a triangular shaped member connected with one

edge of the main body of the protector for covering the rear of the ankle, and fastening means for connecting the other edge of the member with a portion of the other edge of the device. ¹⁰

In testimony whereof I affix my signature.

ADA HENDERSON.
